(57) **CLAIM**

The ornamental design for a slimline health monitoring and diagnostic device, as shown and described.

DESCRIPTION

FIG. 1 is a front perspective view of a slimline health monitoring and diagnostic device in a closed position.

FIG. 2 is a top view of a slimline health monitoring and diagnostic device in a closed position.

FIG. 3 is a left side view of a slimline health monitoring and diagnostic device in a closed position.

FIG. 4 is a front view of a slimline health monitoring and diagnostic device in a closed position.

FIG. 5 is a rear view of a slimline health monitoring and diagnostic device in a closed position.

FIG. 6 is a bottom view of a slimline health monitoring and diagnostic device in a closed position.

FIG. 7 is a front perspective view of an slimline health monitoring and diagnostic device in a open position.

FIG. 8 is a top view of an slimline health monitoring and diagnostic device in a open position.

FIG. 9 is a front view of a slimline health monitoring and diagnostic device in a open position.

FIG. 10 is a rear view of an slimline health monitoring and diagnostic device in a open position.

FIG. 11 is a left side view of an slimline health monitoring and diagnostic device in a open position; and,

FIG. 12 is a bottom view of an slimline health monitoring and diagnostic device in a open position.

The broken line showing is for illustrative purposes only and forms no part of the claimed design.
